UNITED STATES PATENT OFFICE.

GEORGE S. STRONG, OF NEW YORK, N. Y.

JUNCTION-PIECE FOR STEAM-BOILERS.

SPECIFICATION forming part of Letters Patent No. 381,039, dated April 10, 1888.

Application filed January 23, 1888. Serial No. 261,038. (No model.)

To all whom it may concern:

Be it known that I, GEORGE S. STRONG, a citizen of the United States, and a resident of New York city, New York, have invented 5 Improvements in Junction-Pieces for Steam-Boilers, of which the following is a specification.

My invention consists of certain improvements in the construction of the steam-boilers, 10 for which I have obtained United States Patents October 24, 1882, No. 266,551, September 9, 1884, No. 304,973, and April 14, 1885, No. 315,974.

One of the characteristic features of my patented boilers, which are designed more particularly for locomotives, is the combining of two fire-boxes, placed side by side, with the barrel which incloses the combustion-chamber and fire-tubes. The junction-pieces, which form the 20 connection between the fire-boxes and combustion-chamber and between fire-box shell and the barrel, have each the form of a single tube at the end joining the combustion-chamber or barrel, as the case may be, while the 25 other end of each junction-piece which unites with the fire-boxes or fire-box shell flares out into two united segments of tubes.

The junction-pieces, according to my former inventions, were to be made of riveted 30 plates; but such a construction, besides being more or less expensive, has the disadvantage that it is difficult to get all the joints perfectly tight to avoid leakage. To remove this difficulty of liability to leakage, and at the same 35 time to reduce the cost of manufacture of the boilers and increase their efficiency, I draw, press, or stamp the junction-pieces each from a single seamless sheet of metal, as I will now describe.

40 In the accompanying drawings, Figure 1 is a diagram plan of the blank from which the junction-pieces for the fire-boxes and combustion-chamber is made. Figs. 2, 3, 4, 5, 6, and 7 are sectional diagrams showing the successive steps in the drawing, pressing, or stamping operations, Fig. 3 being a section at right angles to Fig. 2, while Fig. 5 is a section at right angles to Fig. 4, and Fig. 7 is a section at right angles to Fig. 6. Fig. 8 is a plan or 45 face view of the partially-formed blank in the condition shown in Figs. 6 and 7. Fig. 9 is a

5 face view of the finished junction-piece ready to be applied. Figs. 1^a to 9^a are corresponding views of the junction-pieces for uniting the fire box shell and barrel of the boiler. Fig. 10 is a longitudinal vertical section of 55 part of the boiler in skeleton. Fig. 11 is a partial sectional plan, and Fig. 12 is a transverse section through the fire box shell.

In the three latter figures, A A are the two 60 tubular fire-boxes, which are corrugated, as set forth in my previous patents, and A' is the fire-box shell, which consists of two tubes, or rather segments of tubes or barrels, united and connected by a plate or cross-braces, a, at their 65 points of junction.

B is the barrel of the boiler, within which are the combustion-chamber C and fire-tubes D.

The fire-boxes are united to the combustion-chamber by the junction-piece E, and the fire-box shell is united to the barrel by the junction-piece F. Each of these junction-pieces has at one end the form of a single tube and at the other the form of united segments of tubes, and I form each junction-piece of a single 75 seamless sheet of metal in the manner which I will now describe.

To make the junction-piece E, I first cut out of a sheet of metal of the proper thickness a blank of the form shown in Fig. 1—that 80 is, of a diamond or lozenge shaped outline with rounded corners and a central opening, p. The blank is put in a press, which has a lower die, 1, of the shape shown in Figs. 2 and 3, an outer clamping-ring, 2, and two upper 85 dies, 3 and 4, one adapted to pass within and through the other. When the sheet Fig. 1 has been placed on the lower die, 1, it is firmly clamped thereto around its margin by the ring 2. The die 3 is now operated to press or draw 90 the sheet down into the lower die, with the effect of bringing the sheet to the dish shape shown in Figs. 4 and 5. The inner die, 4, is now brought into action to press or draw the center of the sheet down to the shape shown in Figs. 95 2 and 3, after which the lower edge of the flaring tube or dish thus formed is flanged, as shown in Figs. 6 and 7. The upper or larger flanged end of this flaring tube is of the lozenge or diamond outline with rounded corners shown 100 in Fig. 8, and like the original sheet, Fig. 1, while the opposite smaller end, similarly

flanged, is of the circular form shown in Fig. 8, of the proper size to correspond with the flanged end of the combustion-chamber, to which it is to be united by these flanges. The 5 larger end of this flaring tube or junction-piece has to have its shape further modified to make it a double tube to be united to the flanged ends of the fire-boxes. For this purpose I introduce into the opposite bowl-shaped ends 10 of the dish filling-pieces or cores in the form of hemispheres, as indicated by dotted lines in Figs. 6 and 8. I then apply to the outside of the dish at the points y suitable side dies, by which those edges of the dish are pressed 15 inward to about the parallel lines m , Fig. 7, and then shaped dies having the contour which those parts of the junction-piece are to finally take are applied to the opposite sides of the dish at the same points to press those sides farther 20 inward to the points indicated by the dotted lines n , Fig. 7, with the result of giving to the junction-piece its final shape (shown in Figs. 9, 10, and 11) as applied to the fire-boxes and combustion-chamber.

25 The operation of drawing, pressing, or stamping up the junction-piece F is substantially similar to that for the junction-piece E, dies being used similar to those shown in Figs. 2 and 3, but of course modified in size and con- 30 tour according to requirements.

A blank of sheet metal of the form shown in Fig. 1^a is placed in the press and clamped to the lower die around its margin by means of a suitable ring, 2, Figs. 2^a and 3^a. The 35 blank is then brought by means of the dies to the dish shape shown in Figs. 4^a and 5^a at a suitable number of successive heats or operations, and then by means of an inner die, similar to the die 4, Figs. 2 and 3, the center of 40 the dish is drawn down, as shown in Figs. 2^a, 3^a, 6^a, and 7^a, the partially-formed blank then

having the shape shown in the plan or face view, Fig. 8.

The hemispherical filling-pieces are placed in the bowl-shaped ends of the dish, as described with reference to Figs. 6 and 8, and by means of suitable outer dies the edges y of the dish are pressed inward first to the parallel positions indicated by the dotted lines m in Fig. 7^a, and then to the final positions indicated by the dotted lines n in Fig. 7^a, and shown more clearly in the front view of the finished junction-piece, Fig. 9^a.

I do not claim in this application the welded fire-box shell shown in the drawings, as that 55 forms the subject of a separate application for a patent filed by me January 23, 1888, Serial No. 261,637.

I claim as my invention—

1. A seamless junction-piece for boilers, one 60 end of the junction-piece having the form of a single tube and the other end united segments of tubes.

2. A seamless junction-piece for the fire-boxes and combustion-chamber of a boiler, one 65 end of the junction-piece being flanged and having the form of a single tube, while the other end is flanged and has the form of united segments of tubes.

3. A seamless junction-piece for boilers, 70 drawn up of a single sheet of metal, one end of the junction-piece having the form of a single tube and the other the form of united segments of tubes.

In testimony whereof I have signed my name 75 to this specification in the presence of two subscribing witnesses.

GEO. S. STRONG.
